DE WITT T. LYON

RADIATOR

Filed Sept. 19, 1924

Patented Aug. 24, 1926.

1,597,082

UNITED STATES PATENT OFFICE.

DE WITT TAYLOR LYON, OF CHICAGO, ILLINOIS, ASSIGNOR OF ONE-HALF TO BABET R. H. LYON, OF CHICAGO, ILLINOIS.

RADIATOR.

Application filed September 19, 1924. Serial No. 738,635.

I have found that when a number of radiator sections are assembled to each other so as to provide a radiator of fifteen or more sections, it is impossible to admit sufficient steam to keep all of the sections warm. If certain of the sections are provided with auxiliary steam inlets so as to permit additional steam pipes to convey steam to the radiator, I have found that the entire length of radiator may be kept sufficiently warm. Since all of the steam condenses before it is conveyed away by the outlet pipe, the same size outlet pipe is large enough to convey away the additional steam that is conveyed to the radiator by the auxiliary steam inlet pipe.

An object of my invention is to provide a radiator which is built up of a number of sections so that the radiator may be made as long as needed and in which certain of the sections are provided with headers that have auxiliary steam inlet openings whereby live steam may be admitted at various points along the entire length of the radiator.

A further object of my invention is to provide a radiator which is simple in construction and in which the headers are shaped so as to interlock, and thus provide a contiguous bottom portion and top portion for the radiator.

Other objects and advantages will appear in the following specification, and the novel features of the invention will be particularly pointed out in the appended claims.

My invention is illustrated in the accompanying drawings forming a part of this application in which:

Figure 1 is a diagrammatic plan view of the device,

Figure 2 is a diagrammatic side elevation of the device,

Figure 3 is a top plan view of one of the headers provided with an extra steam inlet opening,

Figure 4 is a side elevation of Figure 3, and

Figure 5 is a section along the line 5—5 of Figure 3.

In carrying out my invention I provide a plurality of radiator sections indicated by A. In Figures 1 and 2 I have shown these sections diagrammatically, but in Figures 3 and 4 I have shown the special shape of these sections. It will be noted from

Figure 3 that the top header 1 is provided with recesses 2, and projections 3. Each of the headers is provided with the same number of recesses and projections, whereby the headers are adapted to interlock with each other so as to provide a contiguous top to the radiator. In Figure 2 I have shown the top header 1 of one of the sections A as being in communication with the bottom header 4 by means of steam pipes 5. Figure 4 clearly shows how the pipes 5 are secured to the header 1.

Most of the sections have headers which are provided with only one steam inlet opening 6. In Figures 1 and 2 it will be noted that at predetermined intervals a section having a special header is provided, this header having two steam inlet openings 7 and 8. The openings 7 and 8 are in communication with a compartment 9 which in turn conveys the steam to the pipes 5.

From the foregoing description of the various parts of the device, the operation thereof may be readily understood. In operation the sections are assembled in the manner shown in Figure 2 and the sections having additional steam inlet pipes are spaced at predetermined points along the entire length of the radiator. In Figure 1, I have shown the special sections as being spaced every fifth or sixth place along the line of the radiator. A steam inlet pipe 10 composed of sections is connected to the inlet openings 6 and 7 in certain of the sections 1. The pipe sections are screwed into the inlet openings as shown in Figure 2 at 6. The sections which have the openings 8 have steam inlet pipes 12 in communication therewith. If desired, the pipe 12 may be connected to each side of the projections 13 which have the openings 7 and 8 therein. In this way twice the amount of live steam may be admitted to the projection 13 as may be admitted if only one pipe 12 was in communication with the projection 13. The steam flows through the pipes into the top headers 1, then through the pipes 5 and into the lower headers 4. The steam at this point condenses, and the water then flows through the outlet pipe 14.

As shown in Figure 4 the openings 7 and 8 are disposed adjacent to the rear side of the radiator, whereby all of the connections and piping may be disposed at the 110

5 rear of the radiator and therefore be hidden from view. The front of the radiator will therefore resemble a continuous series of unbroken sections and will closely resemble the standard radiators now on the market. The device is extremely simple in construction, and provides a novel means of making a radiator of any desired length and supplying this radiator with the required 10 amount of steam to heat it.

I claim:

15 1. A radiator comprising a plurality of sections adapted to resemble a continuous radiator when assembled, each section having a steam inlet and a steam outlet opening therein, certain of said sections being provided with auxiliary steam inlet openings, whereby additional steam may be admitted to the radiator at various points 20 along the length of the radiator.

20 2. A radiator comprising a plurality of sections each section having an upper and lower header with an inlet and an outlet

opening therein, said headers providing a radiator with a contiguous upper and lower 25 portion, certain of said sections having auxiliary inlet openings, steam pipes in communication with said sections and with said auxiliary openings, whereby additional steam is admitted at various points along 30 the length of the radiator.

3. A radiator comprising a plurality of sections, each section having an upper and lower header with an inlet and an outlet 35 opening therein, pipes placing said upper and lower headers in communication with each other, said headers providing a radiator with a contiguous upper and lower portion, certain of said sections having auxiliary inlet openings, steam pipes in communication with said sections and with said auxiliary openings, whereby steam is admitted at various points along the length 40 of the radiator.

DE WITT TAYLOR LYON.
